UNITED STATES PATENT OFFICE.

WARREN THOMAS NICHOLS, OF HEMPSTEAD, NEW YORK.

FAUCET.

SPECIFICATION forming part of Letters Patent No. 734,355, dated July 21, 1903.

Application filed March 30, 1903. Serial No. 150,216. (No model.)

To all whom it may concern:

Be it known that I, WARREN THOMAS NICHOLS, a citizen of the United States, and a resident of Hempstead, in the county of Nassau 5 and State of New York, have invented a new and Improved Faucet, of which the following is a full, clear, and exact description.

The invention relates to water distribution; and its object is to provide a new and improved faucet which is simple and durable in construction, very effective in operation, and arranged to prevent leakage, as the valve proper is held to its seat by the pressure-supply and opens against the latter when manually actuated.

The invention consists of novel features and parts and combinations of the same, as will be more fully described hereinafter and then pointed out in the claim.

20 A practical embodiment of the invention is represented in the accompanying drawings, forming a part of this specification, in which similar characters of reference indicate corresponding parts in all the views.

25 Figure 1 is a sectional side elevation of the improvement. Fig. 2 is a cross-section of the same on the line 2 2 of Fig. 1. Fig. 3 is a sectional plan view of the same on the line 3 3 of Fig. 1, and Fig. 4 is a similar view of the 30 same on the line 4 4 of Fig. 1.

The valve-body A of the improved faucet is provided with an entrance end A' and a discharge-spout A², and the said entrance end A' is screwed or otherwise secured to the 35 head B' of a pipe B, secured to a suitable support C and connected in the usual manner with a water-supply.

At the entrance end A' of the valve-body A is arranged an integral valve-seat A³, raised 40 in an outward direction—that is, toward the head B'—and on the outer face of the said valve-seat A³ is adapted to be seated a valve D, arranged to open in the direction of the water-supply and normally held to its seat by 45 the water-pressure from the head B'. The valve D is secured on the fluted end of a valve-stem E, extending through and guided in the seat A³, and the said valve-stem extends through the valve-body A and through 50 a cap F, screwing on the outer end of the tubular extension A⁴ of the valve-body A. On the outer end of the valve-stem E is secured

a knob or handle E', adapted to be taken hold of by the operator to push the valve-stem E and its valve D inwardly to move the valve D off 55 its seat in the direction of the pressure of the water-supply.

On the valve-stem E, within the tubular extension A⁴, is arranged a diametrical pin E², extending at its ends into guideways A⁵, 60 formed on the inside of the extension A⁴, to hold the valve-stem E and its valve D from turning. Against the under side of the pin E² rests a washer G, pressed on at its bottom by the upper end of a spring H, coiled on 65 the stem E and resting at its lower end on a deflector A⁶, formed integrally in the valve-body A and arranged below the extension A⁴ to direct the water from the entrance end A' to the spout A².

70 Now when the several parts are in the position shown in Fig. 1 the valve D is held to its seat mainly by the pressure from within the head B', and consequently leakage is not liable to take place at the seat A³. When it 75 is desired to open the valve, the operator presses the knob E' to move the valve D off its seat against the pressure of the water, and at the same time the spring H is pressed, so that on releasing the knob E' the valve-stem 80 is forced back to its upper normal position and the valve D moves to its seat by the pressure of the water in the head B'. It is understood that when the valve D is off its seat water can flow from the inlet end A' through 85 the open valve-seat and the flutes in the stem E to pass into the valve-body A and finally flow from the latter to and through the spout A² to a suitable place of discharge.

The device is very simple and durable in 90 construction, is not liable to easily get out of order, and leakage is prevented by the valve D being held to its raised seat by the pressure of the water.

In case of repairs the body A can be readily 95 unscrewed from the head B' after the water is turned off from the supply-pipe B to give convenient access to the valve D, removable from the end of the stem E.

Having thus described my invention, I 100 claim as new and desire to secure by Letters Patent—

A faucet having a faucet-body provided with a bulged entrance end, a discharge-spout,

a valve-seat at the outer face of the entrance end, a tubular extension between the entrance end and the spout, a valve seated on the said valve-seat at the outer face of the said 5 bulged entrance end, a valve-stem having a fluted end, on which the said valve is secured, the valve-stem extending through the valve-seat, the valve-body and the said tubular extension and forming a guide for the said valve-
10 stem, a spring pressing the said valve-stem, to normally hold the valve to its seat, and a deflector on the inner end of the said tubular extension, to direct the water to the said spout, the deflector forming an abutment for one end 15 of the said spring, said valve-stem extending

upwardly through the said valve-body and a transverse pin extending through said stem at the top of the valve-body, said valve-body having on its inner walls oppositely-disposed vertical slots extending downwardly from its 20 top end, into which slots the ends of said pins are received to hold the valve-stem against rotation, as set forth.

In testimony whereof I have signed my name to this specification in the presence of 25 two subscribing witnesses.

WARREN THOMAS NICHOLS.
